CLAIM

The ornamental design for a foldable media device, as shown and described.

DESCRIPTION

FIG. 1 is a perspective view of the foldable media device showing the new design in a folded state, such that the leftmost panel is on top and the rightmost panel is on the bottom; FIG. 2 is a perspective view of the foldable media device in an expanded state;

FIG. 3 is a top view of the foldable media device in its folded state;

FIG. 4 is a front view of the foldable media device in its folded state;

FIG. 5 is a bottom view of the foldable media device in its folded state;

FIG. 6 is a rear view of the foldable media device in its folded state;

FIG. 7 is a right side view of the foldable media device in its folded state; and,

FIG. 8 is a left side view of the foldable media device in its folded state.
